UNITED STATES PATENT OFFICE.

CORNELIUS G. HASTINGS, OF WEST HOBOKEN, NEW JERSEY, ASSIGNEE TO HASTINGS TUNNEL SYSTEM COMPANY, A CORPORATION OF NEW YORK.

TUNNEL-BLOCK AND TUNNEL CONSTRUCTION.

1,262,041.

Specification of Letters Patent. Patented Apr. 9, 1918.

Application filed October 18, 1915. Serial No. 56,517.

To all whom it may concern:

Be it known that I, CORNELIUS G. HASTINGS, a citizen of the United States, and a resident of the city of West Hoboken, in the county of Hudson and State of New Jersey, have invented certain new and useful Improvements in a Tunnel-Block and Tunnel Construction; and I do hereby declare that the following is a full, clear, and exact description of the same, reference being had to the accompanying drawings, and to the numerals of reference marked thereon, which form a part of this specification.

This invention relates to an improved type of built-up tunnel construction adapted to withstand internal pressure as for instance in cases where the bore is used as a main for the transfer of fluid therethrough. This type of tunnel construction wherein a block embodying the principles of my invention is used, is that used in connection with the tunneling shield disclosed in my co-pending applications for patent for "tunnel constructions", filed July 2nd, 1913, Serial No. 776,898, and "tunneling shields", filed November 19th, 1914, Serial No. 872,921.

It is an object therefore of this invention to construct a reinforced concrete or other composition block provided with suitable reinforcing means and constructed to co-operate with building forms used in assembling the blocks and with mechanisms to hold the blocks in assembled relation to withstand internal pressure.

It is also an object of this invention to construct a reinforced concrete block provided with bars forming the outer edges thereof co-acting with one another when said blocks are arranged in assembled relation to form channels to receive restraining tension rings or tie rods thereabout to withstand pressure from the interior of the structure formed by said blocks.

It is also an object of this invention to provide a block for use in tunnel construction constructed to co-act with restraining means to retain the same in place during the assembly of a number of such blocks to permit withdrawal of said retaining means from engagement therewith and to receive engaged around the exterior thereof retaining bands or rings to hold said blocks closely assembled with one another to resist

bursting stresses on the interior of the structure.

It is furthermore an important object of this invention to construct an improved type of reinforced concrete block, the exterior edges of which are provided with Z-bars whereby the adjacent bars of adjacent rows of blocks form recesses in which reinforcing or retaining bands to maintain said blocks in position are placed to resist internal stresses from within the structure.

It is finally an object of this invention to construct an improved type of tunnel block exceedingly strong and permitting the tunnel to be rapidly built up to the proper shape and form.

The invention (in a preferred form) is illustrated in the drawings and hereinafter more fully described.

In the drawings:

Figure 1 is an elevational view partly in section illustrating the tunnel in the process of construction by use of blocks embodying the principles of my invention.

Fig. 2 is a side elevation thereof.

Fig. 3 is a fragmentary detail section taken on line 3-3 of Fig. 1, with parts broken away and parts shown in elevation.

Fig. 4 is a longitudinal detail view of one of the tunnel blocks broken away at different depths to show the construction thereof.

Fig. 5 is a top plan view of the block.

Fig. 6 is a section on line 6-6 of Fig. 2 with parts omitted.

Fig. 7 is a diagrammatic view illustrating the use of forms in assembling the blocks.

Fig. 8 is a detail view illustrating the connection of segments of the form one to another.

As shown in the drawings: The material of which the block is constructed, concrete or the like, is denoted by the reference numeral 1, and the shape of the block in longitudinal elevation is that of a curved segment, the curvature of which depends upon the contour of the particular tunnel to be built. Molded into the outer edges of each of the blocks 1, are curved bars 2 and 3, respectively of Z-section, and molded within each of said blocks 1, near the side and outer walls thereof, is a continuous strip of wire netting or other foraminous reinforce-

ing material 4, bent to conform to the shape of the block, as clearly shown in Figs. 3 and 6. Also mounted within each of said blocks are five transverse bars or stirrups 5, 5 substantially of U-shape, the legs and outer portion of each of which are disposed within the foraminous material 4, and the outer corner portions of which project through apertures provided in said foraminous material abutting the inner surfaces of the respective Z-bars 2 and 3.

A plurality of apertures 6, are provided transversely through the block 1, intermediate said respective reinforcing bars 5, for 15 a purpose hereinafter pointed out. For the purpose of assembling said blocks to form the walls of a tunnel, which in the present instance is shown as circular, forms are provided which comprise I-beam sections 7, and 20 plates 8, are bolted on each side of the respective webs of said sections at the abutting ends thereof to retain the same assembled in the ring form shown in Fig. 1. The I-beam forms for each layer of the blocks 25 are held spaced from one another by spacer bars 9, one of which is shown in Fig. 7, detachably bolted to the respective webs of the adjacent I-beam forms.

For the purpose of retaining the blocks 30 1, upon the forms, the inner curved surface of the block is provided with a groove lined, if desired, by a channel bar 10. At one or more points in the channel on the inner surface of the block the recess is enlarged 35 to T-shape and the flanges of the channel bar are struck outwardly, as denoted by the reference numeral 11, in Fig. 3, and engaged in said T-shaped recesses are short curved retaining brackets or plates 12, detachably bolted to the web of the I-bar section 7, which act to retain the block upon the I-bar form. As shown, the curvature of said angle iron brackets 12, is such that the same may be readily withdrawn from 45 the T-shaped recesses in the block after said brackets are unbolted from the I-bar form if it is desired to take down and remove the form.

It is sometimes desired to leave the forms 50 and retaining members for the block engaged with the blocks after the same have been completely set up to form the walls of the tunnel, and a lining or facing of concrete or cement 13, shown in Fig. 3, is then 55 applied thereover, and in the view shown in Fig. 3, alternate rows of blocks are shown with the form and retaining means associated therewith, while those rows of blocks therebetween have had the same removed 60 therefrom, to illustrate that either method of erection may be used. To further increase the strength of the structure and particularly to aid the blocks in resisting internal bursting stresses, as for instance when 65 the tunnel or bore is used for the conduc-

tion of fluid, circumferential bars or tie rods 14, are placed therearound in the peripheral grooves formed by the abutting Z-bars 2 and 3, of the adjacent rows of blocks.

For the purpose of positively interlocking the adjacent rows of assembled blocks one to another the apertures 6, extending transversely therethrough are utilized, and telescoping rods 15, and sleeves 16, are used, each of a length substantially equal to that 75 of the width of a block and arranged to break joints as clearly shown in Fig. 2, so that after a block is placed in position engaged over the projecting ends of the rods or sleeves, as the case may be, another rod 80 or sleeve, as the case may be, is inserted into the apertures of the newly placed blocks projecting therebeyond. After the form or tunnel is completed it may be used for any purpose, and as shown in Fig. 1, 85 a bed or foundation 17, is provided, on which tracks 18, are laid.

I am aware that various details of construction may be varied through a wide range without departing from the principles of this invention, and I therefore do not purpose limiting the patent granted otherwise than necessitated by the prior art.

I claim as my invention:

1. A tunnel comprising blocks laid one 95 against another in parallel rows and in staggered relation, each of said blocks having metallic Z bars peripherally recessed into the outer edges thereof affording circumferential grooves between said respective rows of 100 blocks, and retaining rings secured around said tunnel and laid within said exterior circumferential grooves.

2. In a tunnel construction of the class described a plurality of blocks assembled 105 with one another, each of said blocks having Z-shaped metallic bars molded thereinto on the exterior thereof, said bars affording peripheral grooves in the tunnel structure when in assembled relation, and circumferential tie rods fitted in said grooves and extending around the tunnel construction to reinforce the same.

3. In a tunnel construction of the class described a plurality of blocks laid one 115 against the other, means extending transversely through the blocks to interlock the same one with another, members embedded in the periphery of said blocks shaped to form grooves, and mechanism extending circumferentially around the exterior of said blocks, lying in said grooves to reinforce the same and retain the blocks in position.

4. In a tunnel construction of the class described the combination with reinforced concrete blocks built up in staggered relation, of curved bars molded in the outer edges of said blocks whereby adjacent bars of adjacent rows of blocks afford circumferential grooves in a tunnel construction, and rein- 120 125 130

forcing bands extending peripherally around said circumferential grooves to reinforce the tunnel structure against internal bursting stresses.

5. A tunnel construction of the class described comprising a plurality of reinforced concrete blocks, forms on which the same are mounted to form the walls of the tunnel construction, interlocking means between the respective layers of blocks extending transversely through said blocks, Z-bar members recessed into the outer surfaces of said blocks affording a plurality of peripheral exterior grooves in the tunnel construction, and reinforcing members extending peripherally around the tunnel construction and laid within said grooves.

6. A tunnel construction of the class described comprising a plurality of reinforced concrete blocks built up in assembled relation, transverse interlocking means extending between the respective rows of blocks, curved bars embedded in said blocks to form circumferential grooves, and circumferential bands in said grooves extending around said blocks to retain the same in position and resist bursting stresses within the interior of the tunnel construction.

7. In a device of the class described a concrete block, foraminous reinforcing material in said block, reinforcing bars in said blocks having their inner ends bearing against the foraminous material and their

outer ends projecting therethrough, Z bars molded peripherally in the blocks against 35 which the outer ends of the bars abut and reinforcing members secured in channels formed by adjacent Z-bars.

8. In a device of the class described a concrete block, Z members embedded peripherally therein adapted when placed side by side to form channels and members embedded in the block abutting against the peripheral members coacting therewith to reinforce the blocks. 45

9. In a device of the class described a concrete block, Z members embedded peripherally therein, members embedded in the block abutting against the peripheral members 50 coacting therewith to reinforce the blocks and members lying in said Z members extending around the blocks for reinforcing the same.

10. In a device of the class described a concrete block, a plurality of interwoven reinforcing members therein, reinforcing Z members in said blocks and reinforcing members engaged therein. 55

In testimony whereof I have hereunto subscribed my name in the presence of two subscribing witnesses. 60
